UNITED STATES PATENT OFFICE.

SELAH M. BAIRD, OF HOLLY, MICHIGAN.

LIFTING-JACK.

SPECIFICATION forming part of Letters Patent No. 254,255, dated February 28, 1882.

Application filed August 30, 1881. (No model.)

To all whom it may concern:

Be it known that I, SELAH M. BAIRD, of Holly, in the county of Oakland and State of Michigan, have invented certain new and useful Improvements in Lifting-Jacks; and I do hereby declare that the following is a full, clear, and exact description of the invention, that will enable others skilled in the art to which it appertains to make and use the same, reference 5 being had to the accompanying drawing, and to the letters and figures of reference marked thereon, which form a part of this specification.

The same letters and figures of reference are used to indicate the corresponding parts.

15 After describing the invention, its nature and extent will be shown in the claims.

My invention relates to improvements in lifting-jacks.

The novelty of my invention consists in a 20 chain or cord attached to the ordinary lifting-bar, and a bent lifting-arm designed to raise objects resting on or near the ground.

In the drawing, A represents the base; B, the standard; C, the vertical shaft, to which are 25 attached the arm G and the bent arm F. One end of the lever E is pivoted to the vertical shaft C. The bolt a in the standard B is the fulcrum on which the lever E moves.

D represents a spring-catch hook attached 30 to the standard B.

c is a small chain or cord attached to the sliding arm G by means of the button b. The

chain c passes up through the eye-headed bolt d, with the ring e at the upper end of the chain.

The bent arm F is used to elevate objects on 35 or near the ground. When elevated sufficiently high by the bent arm F, the object is then taken by the horizontal arm G and raised to the required position.

The object of the chain c is to raise or lower 40 the arm G to any required position.

The spring-catch D will hold the lever or handle E in a fixed position.

Having now fully described my invention, what I claim, and desire to secure by Letters 45 Patent, is—

1. The bent and curved arm F and the horizontal arm G, both sliding on the vertical shaft C, substantially as shown and described, and for the purposes set forth. 50

2. The chain c, attached to the horizontal arm G, and passing through the eye d, attached to the upper end of the shaft C, in combination with the bent and curved arm F and the horizontal arm G, substantially as shown and described, and for the purposes set forth. 55

In testimony that I claim the foregoing I have hereunto set my hand this 19th day of July, 1881.

SELAH M. BAIRD.
